UNITED STATES PATENT OFFICE

103,630

DESIGN FOR A TEXTILE FABRIC

Elsie J. Das, Honolulu, Territory of Hawaii, assignor to Watumull Brothers, a firm composed of Jhamandas Watumull, Gobindram J. Watumull and Ramchand Watumull, doing business as East India Store, Honolulu, Territory of Hawaii

Application January 4, 1937, Serial No. 66,879

Term of patent 3½ years

To all whom it may concern:

Be it known that I, Elsie J. Das, a citizen of the United States, residing at Honolulu, in the county of Honolulu, Territory of Hawaii, have invented a new, original, and ornamental Design for Textile Fabrics, of which the following is a specification, reference being had to the accompanying drawing, forming part thereof.

In the accompanying drawing the figure is a face view of a textile fabric, showing my new design.

I claim:

The ornamental design for a textile fabric, substantially as shown.

ELsie J. Das.
